Ferdinand, Idaho

Application May 27, 1944, Serial No. 537,615

2 Claims. (Cl. 97—35)

The present invention relates to new and useful improvements in plows, particularly of the tractor-drawn gang type, and has for its primary object to provide, in a manner as hereinafter set forth, an implement of this character comprising means for removing excess straw, stubble, et cetera, from the path of the plows and depositing it in a position to be covered by said plows, thus preventing choking, while at the same time leaving sufficient straw, et cetera, on top of the soil to prevent erosion.

Another very important object of the invention is to provide a plow of the aforementioned character which may be expeditiously adjusted as desired to meet various conditions.

Other objects of the invention are to provide a plow of the character set forth which will be comparatively simple in construction, strong, durable, highly efficient and reliable in use, compact, light in weight and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a top plan view of a plow embodying the present invention.

Figure 2 is a view in side elevation of the implement.

Figure 3 is a fragmentary view in rear elevation, showing the drive means for the forks.

Figure 4 is a view in side elevation of one of the forks and the supporting means therefor, portions of the latter being shown in transverse section.

Figure 5 is a perspective view of an intermediate portion of the crank shaft.

Referring now to the drawings in detail, it will be seen that the embodiment of the invention which has been illustrated comprises a plurality of beams 1 having mounted thereon plows 2. The forward portions of the beams 1 are rigidly connected, as illustrated to advantage in Figure 1 of the drawings. Suitable means 3 is provided for connecting the beams 1 to a tractor or other suitable source of power.

Fixed vertically on the rear portion of the beam 1 of the last plow 2 is a metallic plate 4. A rod 5 is secured for vertical adjustment on the plate 4 through the medium of clamps 6. The rod 5 comprises a laterally projecting lower end

portion constituting a spindle 7 on which a ground wheel 8 is journaled.

Fixed horizontally on the upper, front portion of the plate 4 is a tubular housing 9. A shaft 10 is journaled in the housing 9. The shaft 10 is driven from the wheel 8 through a chain and sprocket connection 11. A suitable tightener 12 is provided for the chain of the drive 11.

Mounted on the beams 1 is a metallic frame structure 13 comprising a horizontal rod 14 and angular members 15. The members 15 terminate in upturned rear end portions on which a horizontal shaft 16 is mounted. Vertical tubular guides 17 are journaled at spaced points on the shaft 16.

Bearings 18 are mounted on the members 15 at the angles thereof. A horizontal crankshaft 19, which parallels the shaft 16 in spaced relation thereto, is journaled in the bearings 18. Clamps 20 are journaled on the throws of the crankshaft 19. Forks 21 are adjustably secured in the clamps 20. The forks 21 include tines or heads 22 on the lower ends of shafts 23. The shafts 23 are adjustably secured in the clamps 20 with their upper end portions slidably engaged in the guides 17.

A suitable universal joint 24 connects the crankshaft 19 to the shaft 10 for actuation thereby. The rod 14 is fixed at one end to the tubular housing 9 to function as a brace therefor.

It is thought that the operation of the invention will be readily apparent from a consideration of the foregoing. Briefly, the ground wheel 8 is adjusted as desired on the plate 4 by loosening the clamps 6 to permit the plows 2 to function at the desired depth. Proper tension on the chain drive 11 is maintained by the tightener 12. As the implement is pulled forwardly with the plows 2 in the ground, the wheel 8 travels on the surface of the ground and is, of course, rotated thereby. Thus, the chain and sprocket connection 11 rotates the shaft 10 which, in turn, drives the crankshaft 19. In this manner the forks 21, or rather the heads 22 thereof, are caused to describe a circular path, the construction and arrangement being such that said forks sweep excess straw, stubble, et cetera, away from in front of the plows 2 to a position where said straw, stubble, et cetera, will be covered by said plows. The clamps 20 permit vertical adjustment of the forks 21 on the crankshaft 19. The shaft 16, on which the forks 21 slide and oscillate, may also be adjusted vertically, if desired, on the members 15 for adjusting or regulating the stroke of said forks.

It is believed that the many advantages of a plow constructed in accordance with the present invention will be readily understood, and although a preferred embodiment of the implement is as illustrated and described, it is to be understood that changes in the details of construction and in the combination and arrangement of parts may be resorted to which will fall within the scope of the invention as claimed.

What is claimed is:

1. A plow comprising a plurality of beams, plows mounted on said beams, a frame structure mounted on the beams, a stationary shaft mounted horizontally on the frame structure, a crank-shaft journaled horizontally on the frame structure below the horizontal plane of the stationary shaft, a plurality of forks slidably and rockably connected to the stationary shaft, means connecting said forks to the crankshaft for actuation thereby for sweeping straw, et cetera, from the path of the plows, a plate mounted on one of the beams, a spindle mounted for vertical adjustment on said plate, a ground wheel journaled on said spindle, and means operatively connecting said ground wheel to the crankshaft.

5 10 15 20 25

2. A plow comprising a plurality of beams, plows mounted on said beams, a frame structure mounted on the beams, a stationary shaft mounted horizontally on the frame structure, a crank-shaft journaled horizontally on the frame structure below the horizontal plane of the stationary shaft, a plurality of forks slidably and rockably connected to the stationary shaft, means connecting said forks to the crankshaft for actuation thereby for sweeping straw, et cetera, from the path of the plows, a plate mounted on one of the beams, a spindle mounted for vertical adjustment on said plate, a ground wheel journaled on said spindle, and means operatively connecting said ground wheel to the crankshaft, the last-named means including a tubular housing mounted horizontally on the plate, a shaft journaled in said housing, a universal joint connecting the third-named shaft to the crankshaft, and a chain and sprocket connection operatively connecting the ground wheel to said third-named shaft.

ORVAL L. BEASLEY,
LEE L. BEASLEY.
